UNITED STATES PATENT OFFICE.

FREDERICK A. SHIMP, OF PHILADELPHIA, PENNSYLVANIA, ASSIGNOR TO SKILL-KRAFTERS INCORPORATED, OF PHILADELPHIA, PENNSYLVANIA, A CORPORATION OF DELAWARE.

DESIGN FOR A RING.

Application filed August 3, 1923. Serial No. 6,938. Term of patent 3½ years.

To all whom it may concern:

Be it known that I, FREDERICK A. SHIMP, and a citizen of the United States, residing in Philadelphia, Pennsylvania, have invented a new, original, and ornamental Design for a Ring, of which the following is a specification, reference being had to the accompanying drawing, forming part thereof, in which—

Fig. 2 is a view in side perspective.

I claim:

The ornamental design for a ring, as shown.

FREDERICK A. SHIMP.
